(57) **CLAIM**

I claim the ornamental design for a protective carrying case for portable electronic devices, as shown and described.

DESCRIPTION

FIG. 1 is a perspective view of a protective carrying case for portable electronic devices showing my new design;

FIG. 2 is a top plan view thereof;

FIG. 3 is a bottom plan view thereof;

FIG. 4 is a right side view thereof;

FIG. 5 is a left side view thereof;

FIG. 6 is a front view thereof; and,

FIG. 7 is a rear view thereof.
